The ornamental design for a remote controller for an audio disc player, as shown and described.

DESCRIPTION

FIG. 1 is a top plan view of a remote controller for an audio disc player showing my new design;
FIG. 2 is a left-side elevational view thereof;
FIG. 3 is a right-side elevational view thereof;
FIG. 4 is a front elevational view thereof;
FIG. 5 is a rear elevational view thereof;
FIG. 6 is a bottom plan view thereof; and,
FIG. 7 is a perspective view thereof, shown in the operating condition.

FIG. 1

FIG. 2

FIG. 4

FIG. 5

FIG. 6
